Dec. 1790

John P. Rathbone of Albany N.Y.

Letters patent No 1790, dated Jan 23, 1863.

The schedule referred to in those Letters Patent and making part of the same.

I, John P. Rathbone, of the City of Albany, State of New York, have reproduced a new Ornamental Design for the door of a cooking Stove, and the plates of its Elevated Oven; and I declare the drawings (Photographs) forming a part of this specification to be a full and complete delineation of the said door and plates with their ornaments; the main door, fire door and back plate not represented being symmetrically similar to their corresponding plates shown.

What I claim as my production, and desire to secure by Letters Patent is the combination and arrangement of figures and forms above described, represented in the drawings, forming together the Ornamental design for the plates of a Cooking Stove.
